COLLAPSIBLE TABLE

Harry A. Reichman, Chicago, Ill.

Application July 20, 1954, Serial No. 444,533

2 Claims. (Cl. 311—83)

The present invention relates to occasional and portable tables and concerns itself more particularly with furniture articles of this class which may be constructed of light weight wire and sheet component parts.

A principal object of the present invention is to devise a light weight yet serviceable knee height occasional table which is adapted to possess decorative yet simple structural features, and which may be easily manipulated between erect and collapsible conditions so that numbers of them may be set up and withdrawn as for informal or buffet uses.

Another object of the present invention is to provide a collapsible and easily portable all-metal table structure which in its collapsed condition occupies extremely narrow dimensions so that numbers of them may be suspended from a side wall projecting nail or hook for storage purposes.

Still another object of the present invention is to provide a light weight foldable occasional table which may be carried as from a finger without involving fatigue, and which may be erected by the simple expedient of descending to engage a floor surface.

For further and more complete understanding of the foregoing and other objects and purposes of this invention, reference will now be had to the accompanying illustrations as well as to the following detailed specification, in both of which like reference numerals designate corresponding parts throughout, and in which:

Fig. 1 is a perspective view on a diminutive scale of a triangular top occasional table having embodied therein various features of the present invention;

Fig. 2 is a plan view with portions broken away of the table illustrated in Fig. 1;

Fig. 3 is an end elevational view of the same table with portions broken away;

Fig. 4 is a side elevational view of the table shown in its partially erected position;

Fig. 5 is a front elevational view of the table in its fully collapsed condition, viewing the bottom surface of the table top; and

Fig. 6 is a fragmentary detailed sectional view taken approximately on line 6—6 of Fig. 2.

In the style which has been arbitrarily selected for illustration, the top 11 of the table is substantially triangular with rounded corners and is contemplated to be made of a single sheet of steel with rolled-over or perpendicular upset edges 12. It will be understood, of course, that the contour or outline of this component is by no means restricted in this manner, but on the contrary the styling, composition and appearance are in no wise inhibited by its functional accessories.

At the underside of the table top there are secured as by riveting or welding a series of strap or anchor brackets 13, 14 and 15, each formed of sheet metallic stock to provide a sleeve or journal portion 16 within which there is housed the pivotable section 17 of a leg assembly.

As best indicated in Figs. 1, 3 and 5, each leg assembly of the three designated 18, 19 and 21 consists of a straight

2

main body portion terminating at its floor engaging end with a rubber knob or thimble 22, and at its secured end with a U-shaped formation of which the perpendicular section 17 is held and pivotable in the sleeve 16 of its related bracket 13, 14 or 15.

Two of the legs indicated 18 and 19 are similar and symmetrically opposite, pivoting from the brackets 14 and 15 whose journal or sleeve portions 16 are for this reason pivotably in axial alignment. The remaining leg 21 is pivoted in an axis parallel to that of legs 18 and 19, but because of the opposite inclination respecting leg 21 as against legs 18 and 19, there is formed therebetween a triangular pedestal support which is permitted to assume the relationship shown in Figs. 1 and 3 as one limit, and that shown in Fig. 5 as an opposite limit. In other words, between the erected position of Figs. 1 and 3 and the collapsed condition of Fig. 5, the leg elements 18, 19 and 21 are controlled as will now be explained.

Legs 18 and 19 cross each other at an intermediate position whereat there is secured thereto as by welding a U-shaped guide or eyelet 25, Figs. 1 and 4, through which the remaining leg 21 is inserted prior to assembly. When the table is engaged for removal as by a single finger, featured in Fig. 4, inserted through the convenience aperture 24 formed in the table top, the leg 21 is withdrawn partially in respect to the guide loop 25 at which time the legs 18 and 19 are permitted to fold back in the direction indicated by the partially collapsed condition featured in Fig. 4. As soon as the table has been lifted clear of engagement with the floor, the leg 21 will be withdrawn to its full extent as shown in Fig. 5 as the legs 18 and 19 drop down. This permits a considerable number of such tables to be stacked one alongside the other and hung as from a wall projection 27 or otherwise until needed.

In order to set up each table for utility position, all that is required to be done is to drop the table until the rubber tips 22 of the legs 18 and 19 engage the floor or ground level. Thereupon the table top 11 will begin to pivot about the common axis through hinge brackets 14 and 15 as the leg 21 descends into the position first as shown in Fig. 4 and then ultimately as that shown in Figs. 1 and 3. When the leveling off position is achieved, a pin or formed projection 28 in the leg 21 will strike against the top of loop 24 assuring the triangular spread between the three legs required to attain leveling of the table top 11.

When a number of these tables are to be erected for use, the last described operation will be found facile and expedient. As soon as the table is set down so that the extremities 22 of the joined legs 18 and 19 touch the ground, the remaining leg 21 begins to slide within its guide 24 until it assumes a substantially equi-angular relationship as shown in Fig. 3, an accomplishment that may be executed solely by the gravitational effect and with but minor guidance from the operator.

It is to be noted that the aforescribed occasional table construction lends itself to being mass produced and assembled so as to be marketable economically for popular appeal. The table top may be shaped with almost infinite design variations and is capable of receiving enameling, finishing and ornamentation of widely different styles and quality.

While the present invention has been explained and described with reference to a specific structural contemplation, it will be understood nevertheless that various changes and modifications are susceptible of being incorporated without departing from its essential spirit or scope.

The invention claimed is:

1. A collapsible table comprising a rigid top and three legs hinged to the bottom thereof, two of said legs hinging about a common axis, the third leg hinging about an axis

3

spaced from said common axis and swinging in a plane intermediate the planes of motion of said two legs, a loop member rigidly attached to said two legs at a junction point intermediate the lengths thereof and binding them rigidly together, said third leg passing through said loop and slideable therein, and a protuberance formed on said third leg limiting the movement of said legs to a point where said third leg is advanced to a position at which the feet of the three legs form a triangle so as to constitute a stable support for the table when the latter is set up, said protuberance leaving the third leg free for retraction by a simple lifting movement of the table top at one side thereof causing the third leg to slide upward in the loop to a position in which all three legs are in a substantially common plane close to the table top.

2. A collapsible table as defined in claim 1 including

5 formed with horizontally extending bearing portions, and said legs being bent at their upper extremities to form horizontally extending pivot portions, respectively housed in said bearing portions.
